CARTRIDGE FOR MAGNETIC TAPE

Arnold J. Butler, Wappingers Falls, and Arnold M. Davis and Joseph F. Talerico, Poughkeepsie, N.Y., assignors to International Business Machines Corporation, New York, N.Y., a corporation of New York

Filed Aug. 10, 1960, Ser. No. 61,689

Term of patent 14 years

(Cl. D26—14)

FIG. 1

FIG. 2

FIG. 1 is a perspective view of the front and left hand side of a cartridge for magnetic tape showing our new design.

FIG. 2 is a perspective view of the rear and right hand side thereof.

The essential features of the design reside in the portions shown in full lines.

The bottom of the cartridge is flat and unornamented.

We claim:

The ornamental design for a cartridge for magnetic tape, substantially as shown and described.
